UNITED STATES PATENT OFFICE.

WILLIAM BOLLENBACHER, OF BELLEVUE, OHIO.

CHILD'S TOY.

1,305,517.

Specification of Letters Patent. Patented June 3, 1919.

Application filed June 17, 1918. Serial No. 240,532.

To all whom it may concern:

Be it known that I, WILLIAM BOLLENBACHER, a citizen of the United States, residing at Bellevue, in the county of Sandusky and State of Ohio, have invented certain new and useful Improvements in Children's Toys, of which the following is a specification.

This invention relates to the toys known as rocking horses or hobby horses; and it consists in the novel construction and combination of the parts hereinafter fully described and claimed.

In the drawings, the figure shows a perspective view of a toy constructed according to this invention.

A supporting post E is provided having a forked upper end portion e'. This post is supported above the floor upon four curved legs A A and a a. These legs radiate from the lower part of the post to which they are rigidly secured, and they preferably have rollers f at their lower ends. The front and rear legs a a are arranged in line with each other, and they are longer than the legs A A which project laterally.

A rocking board B is provided and it has a lug b' on the middle part of its underside which is pivoted by a pin e in the forked portion of the post E.

The rear portion b of the board B forms a suitable seat for the child, and a helical spring d is arranged between its front end portion c and the front leg a underneath it. An ornamental piece D is also secured to the front part c, and is shaped to represent the head and neck of a horse.

The child can place its feet on the cross legs A if desired, and can rock the rocking board by suitable movements of its body, 40 against the tension of the spring. The long legs a prevent the rocking movements of the child from tipping over the toy in a longitudinal direction, and the relatively short legs A are sufficient to prevent the load from 45 tipping over laterally.

What I claim is:

A child's toy, comprising a supporting post, a rocking board pivoted at its middle part to the upper end of the post and having 50 a seat portion at its rear end, legs rigidly secured to the said post and arranged radi ally of it, the front and rear legs being ar ranged in line with each other under the said board and being longer than the side 55 legs, and a spring arranged between the front leg and the front end portion of the board.

WILLIAM BOLLENBACHER.
